TELEPHONE HANDSET

Herbert F. Obergfell, River Forest, Ill., assignor
to Associated Electric Laboratories, Inc., Chi-
cago, Ill., a corporation of Delaware

Application May 12, 1932, Serial No. 610,895

7 Claims. (Cl. 174—103)

This invention relates to improvements in handset combinations for use in telephone instruments. As is well-known these handset combinations comprise a handle portion having a receiver incorporated in one end and a transmitter in the other end so that when the handset is in use the receiver is brought to the ear and the transmitter adjacent the mouth of the user, and the principal object of the invention resides in the design of a handset in which neatness and economical manufacture, together with durability and ease of assembly, are combined.

A further object of the invention is to design a handset which can accommodate any one of a number of different transmitter units and mouthpieces so that the handset can be constructed standard for all of them.

Another object of the invention is to design a transmitter mouthpiece so that it is not necessary to provide special fixing arrangements for insuring that the opening in the mouthpiece comes directly opposite the mouth of the user. In accordance with this object a particular feature of the invention resides in a novel transmitter mouthpiece which does not require mounting in a particular position and in which the sound waves can enter it from any angle.

A further feature of the invention is concerned with a transmitter unit which is secured in the handset opening between a pair of metal plates which also serve to carry current to one of the electrodes of the transmitter, while the other electrode makes contact with a spring member in the bottom of the handset upon which the transmitter rests. Other features have to do with the means for supporting the metal plates in the bottom of the handset opening which means at the same time serve as terminal points for the connection of the leadin wires.

Other features not specifically pointed out will be apparent hereinafter in the detailed description which, together with the drawing, relate to a preferred embodiment of the invention.

In the drawing, Fig. 1 shows a side cross-sectional elevation of a complete handset unit with the transmitter and receiver units shown in full lines; Fig. 2 is a view of a well-known standard type of transmitter unit and associated mouthpiece shown in the handset of Fig. 1 to indicate the interchangeability of the different types of transmitter units; Fig. 3 shows a full front elevation of the transmitter end of the handset with the transmitter unit removed; Fig. 4 is a perspective elevation of one of the arcuate metal plates 16 for supporting the transmitter unit; while Fig. 5 is a diagrammatic illustration of the circuit connections extending to the various terminal points in the handset.

Referring now more particularly to Fig. 1, the handset comprises a single moulded unit 5, pref-

erably made of bakelite having a handle portion so that it may be taken hold of by a person using this device. There is an enlarged opening or casing on each end of the handle, in one of which any well known receiver unit 6 is placed and held in position by the round ear piece 7 which is screwed down over the opening in the handle 5. The transmitter unit 8 is supported in the opening in the other end of the handle 5 and held in place by the circular mouthpiece 9 having a number of radial slots 10 cut into it for the entrance of the sound waves. The mouthpiece 9 is clamped on the front side of the transmitter unit 8 and the opening of the handset 5 by means of the metal ring 11 threaded on the outside of the opening in the handset. The mouthpiece 9 being circular in shape and having the openings 10 arranged circumferentially and evenly spaced around its surface does not require any particular set position with regard to the transmitter unit 80 and the mouth of the person using the device. It may be turned axially to any position in assembling it and the metal ring 11 screwed down tight. The sound waves will enter the openings 10 from any direction. The transmitter unit 8 85 has a flange 12 formed on it extending around its periphery against the front side of which the mouthpiece 9 presses when in place.

A pair of arcuate shaped metal plates 16 and 17 are supported on opposite sides of the bottom 90 of the opening in the handset 5 by means of a pair of integral ears 18 which are engaged by the mounting screws 19 threaded into shoulders formed or moulded in the bottom of the opening. The openings adjacent the ears 18 in the plates 95 permit a screw driver to turn the screws 19 into position. The screws 19 in addition to holding the arcuate metal plates 16 and 17 in the opening serve as terminal screws for the attachment of the connecting wires. The flange or shoulder 100 12 on the transmitter unit 8 abuts the top edge of the metal plates 16 and 17 when the mouthpiece 9 is screwed down by the metal band 11 against the front side of the shoulder 12. The transmitter unit 8 is, thereby securely held in 105 its position in the opening of the handset. An electrode at the bottom of the center of the transmitter unit 8 has a projection 20 extending outwardly therefrom which engages a flexible leaf spring 21 secured by the terminal screw 22 in the bottom of the casing. The arcuate metal plates 16 and 17 in addition to butting up against the flange 12 of the transmitter 8 frictionally engage the sides of the transmitter unit, due to their resiliency.

It will be noted that the transmitter unit 8 has no external protruding terminal screws or binding posts for the attachment of the connecting wires. In order to provide for connections to the transmitter 8, advantage is taken of the 115 120

fact that the handset unit 5 is constructed of moulded bakelite which is inherently of insulating property. In the arrangement disclosed in Fig. 1 and diagrammatically in Fig. 5 one of the connecting leads to the transmitter 8 is attached to the screw 22 and carries current from the line through the receiver unit 6 to the flexible leaf spring 21 which in turn bears against the shank 20 of the rear electrode and this in turn, in the well-known manner, extends the current through the carbon granules and then to the front electrode. The front electrode is directly connected in any suitable manner to the metal casing or container which encloses the transmitter 8. The circuit of the current path then extends from the outside surface of the transmitter 8 to one or the other of the arcuate metal plates 16 or 17 with which the unit is in engagement and out to the line wires. The terminal screws 19 in addition to supporting the plates 16 and 17 by the ears 18 secure the connecting wires thereto. An opening 35 in the transmitter end of the handset 5 permits entrance of the connecting wires while the conductors extending between the transmitter unit and the receiver unit extend through the metal tube 36 which is moulded inside of the handle 5. This metal tube 36 likewise serves to lend rigidity and strength to the handle portion of the handset 5.

Referring now more particularly to Fig. 2, the handle portion 5 of the handset including the opening of the transmitter casing is of exactly the same construction as that shown in Fig. 1. The transmitter unit 32, however, is of a different type of construction from that of the transmitter 8 of Fig. 1 in that the connecting terminals for the attachment of the electrical conductors are mounted directly on to the rear of the transmitter unit. Additional connecting wires between the terminals 19 in the bottom of the casing of the handset 5 must, therefore, be provided for connecting with the terminals on the rear side of the transmitter unit. Because of the position of the terminal connecting screws on the rear of the transmitter unit 32 this unit must be set in a certain particular position. In the opening of the casing of the handset 5 so that it cannot be rotated as the transmitter unit 8 of Fig. 1 can be rotated axially. For this purpose a keyway on the rear side of one point of the transmitter 32 is engaged by a raised portion 34 in the periphery of the casing of the handset opening and locks it in position.

The mouthpiece 30 containing sound openings 31 is of a slightly different construction from the mouthpiece 9 of Fig. 1. It must be mounted on the handset in a particular position so that sound waves can enter its openings from only a certain direction and for this reason it must be secured so that it cannot be rotated axially. For this purpose suitable lugs on opposite sides of the rear of the mouthpiece 30 engage slots 33 on opposite sides of the periphery of the transmitter unit 32. The metal ring 11 which is the same as the metal ring 11 of Fig. 1 clamps on the outside of the casing of the handset 5 and holds the mouthpiece 30 directly on the front side of the transmitter 32 which in turn rests on the edge of the opening in the handset.

It will be seen that by merely inserting the arcuate metal plates 16 and 17 into the bottom of the casing and using the screws 19 to hold them in place, the transmitter unit 8 of Fig. 1 together with its mouthpiece 9 may be substituted in place of the transmitter 32 and mouth-

piece 30. This renders it unnecessary to provide two different kinds of handles 5 and their openings on each end for different kinds of transmitter units and their associated mouthpieces. The handle may then be said to be of universal construction.

What is claimed is:

1. In a transmitter casing, a transmitter unit therein, a pair of arcuate shaped members in said casing resiliently engaging opposite sides of said transmitter unit to support the transmitter in position, means for securing said members in said casing and at the same time terminating connecting wires thereto, said members extending electrical connections between said transmitter unit and said connecting wires. 80
2. In a transmitter casing, a transmitter unit therein, arcuate metal plates resiliently engaging opposite sides of said transmitter unit to support it in said casing and to complete electrical circuits thereto, and mounting screws for fastening said metal plates in said casing and for securing connecting wires thereto. 95
3. In a transmitter casing, a transmitter unit therein, arcuate plates fastened to said casing and resiliently engaging opposite sides of said transmitter unit to support it in position, said plates serving to carry current to said transmitter, a mouthpiece for said transmitter, and means for clamping said transmitter between said mouthpiece and said arcuate plates. 105
4. In a transmitter casing, a transmitter unit therein, arcuate metal plates secured in said casing and frictionally engaging opposite sides of the transmitter unit, said plates supporting said transmitter in said casing and extending electrical connections thereto, a mouthpiece for said transmitter unit, and means for securing said mouthpiece to said casing so that it also holds said transmitter unit against the edges of said metal plates. 110
5. In a transmitter casing, a pair of transmitter units, one or the other of said units adapted to be placed in said casing, said first unit having electrical connections made to it previously to its placement in said casing, said other unit having electrical connections made to it consequent to its placement in said casing, and an adapter member in said casing in case said other unit is placed therein, establishing electrical connection therewith and securing the unit therein. 115
6. In a transmitter casing, a transmitter unit in said casing, said transmitter unit having notches on opposite sides of its periphery, a mouth piece covering the front of said transmitter unit and having lugs on opposite sides of its periphery engaging the notches in said transmitter unit to prevent axial rotation of the mouth piece, and a clamping ring threaded onto said casing clamping said mouthpiece to said transmitter unit. 125
7. In a transmitter casing, a transmitter unit in said casing, a keyway at one edge of the rear of said transmitter unit, a lug in the periphery of said casing engaging said keyway in said unit to prevent axial rotation of the transmitter with respect to said casing, said transmitter unit having notches on opposite sides of its front surface, a mouthpiece covering the front of said transmitter and having lugs on opposite sides of its rear engaging the notches in said transmitter to prevent axial rotation of the mouthpiece with respect to said transmitter, and a clamping ring threaded onto said casing to clamp said mouthpiece and transmitter unit together to said casing. 140
